UNITED STATES PATENT OFFICE.

DE FOREST S. STONE, OF TAKOMA PARK, MARYLAND.

JOGGING MECHANISM FOR PRINTING PRESSES.

1,408,419.

Specification of Letters Patent. Patented Feb. 28, 1922.

Application filed February 21, 1921. Serial No. 446,596.

To all whom it may concern:

Be it known that I, DE FOREST S. STONE, a citizen of the United States, residing at Takoma Park, in the county of Montgomery and State of Maryland, have invented certain new and useful Improvements in Jogging Mechanism for Printing Presses; and I do hereby declare the following to be a full, clear, and exact description of the invention, such as will enable others skilled in the art to which it appertains to make and use the same.

This invention has relation to printing presses of the type which may be termed self feeding presses and the invention has particular relation to jogging mechanism for the feeder.

The invention has for another object the provision of a jogging mechanism which may be employed in connection with the feeding mechanism of the printing press to engage the sheet of paper, cards or the like as the same are delivered to the receiving table to properly aline the printed sheets, cards or other members and retain the same in an ordinary pile during the operation of the printing press and feeding mechanism.

Another object of the invention resides in the provision of a jogging mechanism of the character stated which will be especially adapted for use in connection with the conventional form of feeder such as the type known to the trade as the Humana designed for use on printing presses of the Gordon type.

The invention has for another object the provision of a jogging mechanism of the character stated which may be constructed for attachment to the feeding mechanism and cooperation with the latter for engagement with the pile of printed sheets, cards and the like as each printed sheet or card is delivered to the paper box or receiving table, thereby leaving the printed sheets or cards in proper order and alinement.

A further object of the invention resides in the provision of jogging mechanism of the character stated which may be readily adjusted for sheets, cards or the like of various sizes without in any manner interfering with or altering the construction or operation of the feeding mechanism or the jogging mechanism.

A further object of the invention resides in the provision of jogging mechanism of the character stated which will be construct-

ed and arranged in such a manner that the paper engaging members may be moved away from the pile automatically during the delivery of a new printed sheet or card to 60 the pile and then will be automatically returned to operative position to again engage the pile at the ends thereof, the edge of the pile and on the upper face of the pile adjacent the lower edge, thereby causing the 65 new printed sheet or card to be properly alined with the pile and prevent turning or curling of the new printed sheet or card.

The invention has for a further object the provision of a jogging mechanism of the 70 character stated in which the several paper engaging members may be positioned and connected in such a manner to the other parts of the printing mechanism and located with respect to the movable parts of 75 the feeding mechanism so that they will be operated properly and accurately during the several movements of the paper feeding box or table and the other parts of the feeding mechanism such as the long levers or 80 rocking levers of the mechanism for delivering printed sheets or cards to the paper box or table and the main sucker arms or operating levers for the unprinted paper feeding mechanism or press feeding mechanism. 85

The invention has for a still further object the provision of a jogging mechanism of the character stated in which the controlling members of the various paper engaging members may be readily regulated 90 to properly position said paper engaging members according to the size of the sheets or cards to be delivered to the paper box or receiving table. 95

A still further object of the invention resides in the provision of a jogging mechanism of the character stated which will be simple in construction and operation, composed of the minimum number of parts and 100 highly efficient for the purpose for which it is intended.

With the foregoing and other objects in view, as will appear as the description proceeds, the invention consists in the novel construction and arrangement of cooperating elements as hereinafter more specifically set forth, claimed and shown in the accompanying drawings forming a part of the present application and in which:— 110

Figure 1 is a rear elevation of the feeding mechanism known to the trade as the Hu-

mana feeder and specially adapted for attachment to the printing presses of the Gordon type, this view showing my improved jogging mechanism applied to the feeder.

5 Figure 2 is a vertical section through the parts shown in Figure 1 with the long levers or gripper bars carrying levers of the printed sheet delivering mechanism in their innermost position and the main sucker arms in 10 their outermost position.

Figure 3 is an enlarged detail view in longitudinal section through the upper portion of the paper box or receiving table to show clearly the upper jogging arm and the 15 mounting thereof.

Figure 4 is a detail section through the upper jogging arm as shown on line 4—4 of Figure 3.

20 Figure 5 is an enlarged detail perspective view of the upper jogger arm removed.

Figure 6 is an enlarged plan view of a portion of the paper receiving table with the parts mounted in their operated positions.

25 Figure 7 is an enlarged plan of a portion of the lower edge of the jogging table, showing a portion of the parts disclosed in Figure 6 but with the jogging mechanism in inoperative position.

30 Figure 8 is an enlarged detail vertical section on the plane of line 8—8 of Figure 6, looking in the direction indicated by the arrows.

35 Figure 9 is an enlarged detail elevation of one of the end jogger bars and the supporting means therefor.

40 Figure 10 is a detail view on the plane of line 10—10 of Figure 6, looking in the direction indicated by the arrows and partly in section, this view showing only the construction of one of the end jogger bars and the supporting means therefor.

45 Figure 11 is a detail enlarged section on the plane of line 11—11 of Figure 10, looking in the direction indicated by the arrows.

50 Figure 12 is a view similar to Figure 10, showing the extension arms for the end jogging bar in folded position.

Figure 13 is an elevation at right angles to Figure 12, showing the extension arms 55 for the end jogging bar in folded position.

Figure 14 is a vertical detail section substantially on the plane of line 14—14 of Figure 15, looking in the direction indicated by the arrows, the parts being shown on an enlarged scale in Figure 14.

60 Figure 15 is a detail vertical section at right angles to Figure 14 and taken substantially on the plane of line 15—15 of Figure 14, looking in the direction indicated by the arrows.

Figure 16 is a detail section substantially on the plane of line 16—16 of Figure 14, looking in the direction indicated by the arrows.

65 Figure 17 is a detail view of the adjust-

able block for the lower paper engaging finger carrying member, removed.

Referring more in detail to the drawings, it will be understood that similar reference characters designate corresponding parts throughout the several views of the drawings when referring to the various parts of the invention throughout the following paragraphs.

In order that the present invention may be 75 readily understood I have shown the same as being applied to the form of feeder known as the Humana and which is designed especially for printing presses of the Gordon type. I have only shown in the drawings, 80 however, some of the principal parts of this feeder, a portion of the frame thereof being indicated at 10 while 11 designates the clamps by means of which the lower ends of the long operating levers 12 of the feeding 85 mechanism are connected with the printing press frame. The long levers 12 are pivotally mounted for rocking movement at their lower ends on the cross bar 14 carried in supports at the outer ends of the clamps 11. A 90 pair of spaced connecting bars 15 extend between the long levers 12 and these bars 15 are non-rotatable. The bars 15 are located a short distance above the cross bar 14. The upper ends of the rock levers 12 and the 95 parts carried thereby are not disclosed in the present drawings as this is unnecessary. The present invention may be disclosed clearly without showing all of the parts of the feeding mechanism. The main sucker arms 16 100

of the feeding mechanism are disclosed and these arms are in the form of upper or shorter rocking levers and may be termed operating levers of the mechanism for feeding the unprinted sheets or cards to the press. 105 These main sucker arms 16 are of the usual form and mounted in the ordinary manner, as will be clearly understood by referring to Figure 2 of the drawings. The upper end of one of these main sucker arms 16 serves 110 to carry the sucker bar but this member is not shown as the upper portions of the main sucker arms are cut away, for the sake of clearness. The printing paper receiving box or table 18 is also shown in the drawings and 115 this table which may be termed the jogging table, owing to the attachment of the jogging mechanism forming the subject matter of the present application, is hingedly mounted at its upper end to the supporting member 19 120

which rests upon the stationary transverse frame member 20, in the usual manner. The form of feeding mechanism disclosed in order to show the application of the present jogging mechanism, also includes a pair of 125 forwardly directed arms 21 carried by the upper bar 15 and connected at their forward ends by rigid cross bar 22 to which is connected in a conventional manner one end of helical expansion springs 23, the opposite 130

end of which is connected in a similar manner to the lower cross bar or spring carrying bar 24 connecting the lower ends of the main sucker arms 16. The feeding mechanism further includes a paper receiving box or table operating rod 25 which is hinged at its upper end, as shown at 26, to the lower face of the table 18, adjacent the transverse center of the lower edge thereof. This rod 25 has its lower end portion extended through a collar 27 projecting from and rotatable on the upper bar 15. One or more stop collars 28 may be adjustably mounted on the rod 25 to regulate the movement thereof during the initial adjustment of said rod 25 and the rod 25 may be secured in its adjusted position by a set screw 29 or the like mounted in the collar 27, thereby regulating and limiting the rocking movement of the jogging table 18 during operation of the feeding mechanism. All of the parts so far described are included in the form of feeding mechanism above mentioned and while the form of the present invention as shown in the accompanying drawings are to be described in detail the following paragraph is especially adapted to the Humana feeder, I do not claim the feeder to be a part of the present invention.

The present invention includes an upper jogging arm 40, end jogging members 56 and lower jogging fingers 95, which cooperate in jogging the paper or cards as they are delivered in a pile upon the jogging table 18, movement of the sheets or cards toward the lower edge of the jogging table 18 being limited in the usual manner by the lower stop plates 18^a which are adjustably mounted upon the jogging table 18 by the supporting members 18^b adjustable along the slots 18^c in the jogging table 18, as shown in Figures 1 and 6 of the drawings. The construction and mounting of the lower stop plates 18^a which constitute part of the feeding mechanism, however, need not be varied when the present invention is applied to the feeding mechanism.

The upper jogging arm 40 works through an elongated slot 41 formed in the upper portion of the jogging table 18 and extending downwardly from the upper edge thereof, at the transverse center of the jogging table 18. This is shown clearly in Figures 1 and 3 of the drawings. The upper jogging arm 40 has a forward side extension member 42 which is formed for sliding engagement in a dovetailed groove 43 in the forward side of the lower side of the upper jogging arm so that the height of the same may be increased, as occasion may require. A screw 42' mounted by arm 40 is engageable against slide 42 to secure it in adjusted position. This upper jogging arm 40 has an enlarged portion 44 adjacent its lower end and beneath the jogging table 18. A set screw 45 is extended through this enlarged portion 44 and through an adjustably mounted collar 46 carried on a stationary supporting bar 47 projecting rearwardly from the stationary frame member 20. The stationary 70 supporting bar 47 may be squared in cross section to correspond with the bore of the sleeve 46 and this sleeve 46 may be readily adjusted longitudinally of the bar 47 and the set screw 45 tightened to bear against the bar 47 and prevent movement of the sleeve 46. The upper jogging arm 40 is free at all times, however, to rotate upon the smooth portion of the shank of the set screw 45 between the collar 46 and the head 75 formed on the other end of said screw 45, as will be clearly understood by reference to Figure 4.

The greater portion of the upper jogging arm 40 projects upwardly through the slot 85 41 of the jogging table 18. The lower extremity of the upper jogging arm 40, beneath the rigid supporting bar 47 is bifurcated, as shown at 48, and has the upper forward end of a telescoping operating rod 49 pivoted thereto, as shown at 50. This section of the rod 48 is adjustable in the outer section 51, which is preferably hollow and a set screw 52 or the like is employed to secure together the sections of the operating rod 49 after 90 they have been properly adjusted one upon the other. The lower or rear end of the section 51 of the operating rod 49 is pivoted, as shown at 53, to a laterally projecting ear 54 of a collar 54 which is adapted to be secured in adjusted position upon the upper portion of the jogging table operating rod 25, by a set screw 55 or the like. It will therefore be seen that the operating means of the upper jogging arm 40 is disposed for 95 movement by the jogging table 18 and the operating rod 25 therefor, as will be later more fully set forth.

The jogging bars 56 have bottom extensions slides 57 working in suitable dovetailed grooves 58 in the inner side faces thereof and secured in adjusted position by suitable screws or the like 59 tightened against the same. These plates 57 may be readily lowered by loosening screws 59 and thereafter secured in adjusted position by tightening said screws so as to ride upon the upper face of the jogging table 18 in front of the anti-friction rollers 60 which are loosely mounted in the rear portions of the 100 bifurcated enlarged lower ends 61 of the end jogging bars 56, as clearly shown in Figures 2, 9, 10, 11, 12 and 13 of the drawings. These end jogging bars 56 also have a pair of spaced upper and lower ears 62 projecting 105 from their rear faces, the purpose of which will presently appear.

Sectional upper and lower arms 63 are provided for each end jogging bar 56 and are pivotally mounted on opposite sides of the 110

115

120

125

130

ears 62 so that these arms 63 may be folded against the outer sides of said end jogging arms 56, at times, as shown in Figures 12 and 13 of the drawings. The sectional arms 63 are adapted to be adjusted longitudinally, owing to slots 64 in one section of the arm 63 while guide studs 65 are carried at the outer extension of the other section of each arm 63 and extended through the guide 10 slots 64. The outer ends of the adjustable arms 63 are pivotally mounted on the ends of the short upper leg 66 and comparatively long lower leg 67 of the bifurcated end portions 68 of the sliding bars 69. The sliding 15 bars 69 are extended above the jogging table 18 adjacent the opposite ends thereof and are adapted to be moved toward and away from the upstanding end flanges 18^a, as may be readily understood by referring to 20 Figures 1, 6 and 7 of the drawings. The lower ends of the bar 69 are offset, as shown at 70, and connected with sliding sleeves 71 on opposite end portions of a stationary transverse shaft 72, which latter is mounted 25 in the upturned ends 73 of the bar 74 secured upon the upper face of the lower transverse edge of the jogging table 18. In order to resiliently retain the rods 69 in their outermost position, or unoperated position 30 toward the upstanding end flanges 18^a of the jogging table 18, I have provided a pair of expansion springs 74' which are mounted on the stationary shaft 72 between the sleeves 71 and stop pins 75 which latter 35 may be secured in any one of the series of openings 76 extending transversely through the stationary shaft 72, said springs 74' serving to force the sliding sleeves 71 toward the ends of the stationary shaft 72, as will be 40 readily understood by referring to the drawings.

As actuating means for the bars 69, I have provided a pair of actuating rods 77 which are pivoted to the sleeves 71 and connected 45 with opposite arms 78 of a cross head on T 79, as clearly shown in Figures 1, 2, 6, 7 and 8. This cross head or T 79 is mounted on the squared portion 80 of a turn rod 81 which has a reduced upper rounded portion 50 82 extended through a rearwardly directed lug 83 projecting from the central portion of the stationary shaft 72. A suitable fastening pin 84 is extended through the upper portion 82 of the turn rod 81 and a suitable 55 washer 85 or the like may also be placed around this end 82 beneath the locking pin 84 to permit of ready turning of the turn pin 81. The portion of the turn pin 81 beneath the squared portion 80 thereof is engaged 60 in a socket 86 in the upper end of a non-rotating rod 87 which works through the depending guide sleeve 88 formed on an outwardly or rearwardly projecting central lug 89 of the stationary bar 74. The turn pin 81 has a spiral groove 90 in its depend-

ing portion and within which is engaged the lug 91 formed on the inner wall of the socket 86, adjacent the upper end thereof, whereby longitudinal movement of the rod 87 through the guide sleeve 88 will cause rotation of the 70 turn pin 81 to turn the cross head 78 and thereby actuate the bar 69, as shown in Figure 6 of the drawings. It will be understood that the upward longitudinal movement of the rod 87 in the guide sleeve 88 causes sliding movement of the sleeve 71 on the stationary shaft 72 and thereby drawing the rods 69 toward one another, against the action of the spring 74'. As the springs 74' are permitted to expand, however, the sleeve 80 71 will be forced toward the ends of the stationary shaft 72, thereby returning the arms 69 to their outermost or unoperated position, as may be later clearly understood. 75

The upper portion of the rod 87 is straight 85 while the lower portion thereof is curved slightly forwardly, as shown clearly in Figure 2 of the drawings. On this lower curved portion is adjustably mounted a collar 92 adapted to be secured in adjusted position 90 by a set screw or the like 93. This collar 92 carries a depending arm 94 which is turned and curved rearwardly and upwardly, as shown at 94' for engagement upon the cross bar 24, as also shown clearly in Figure 95 2 of the drawings. It is to be understood, however, that during part of the operation of the feeder and the jogging attachment, the bar 24 moves rearwardly from beneath the arm 94 but may freely return to position 100 beneath the same, owing to the curvature of the end 94' of the arm 94. This may be more clearly understood as the description proceeds.

The lower jogging fingers 95, previously 105 mentioned, and of which I have shown two in the drawings, are adapted to work through vertical slots 96 in the lower transverse paper stop plate 18^a, so that the working beveled ends 97 may be brought down 110 upon the upper face of each sheet or card after the same is delivered to the pile and thereby prevent curling of the lower edges of the sheets or cards delivered to the jogging table 18. Each lower jogging finger 115 95 is mounted transversely upon the upper end of a reciprocating supporting bar 98, by means of a fastening member 99 extended through an elongated slot 100 in the main portion of the finger 95, downwardly 120 of the lower paper stop plate 18^a, as shown in Figure 14 of the drawings. Each lower jogging finger 95 is extended parallel with the floor of the jogging table 18 and remains parallel therewith during reciprocating movement of the supporting bar 98. Each supporting bar 98 is adapted to reciprocate through a slot 101 in a guide block 102 which is adapted to be adjusted longitudinally of the jogging table 18, said block 130

102 having a reduced central or neck portion 103 which is engaged in an elongated longitudinal slot 104 in the jogging table 18. It will be understood that the reciprocating 5 supporting bar 98 also works through the slot 104 and the block 102 may be secured in adjusted position in the jogging table 18 by suitable securing members 105. The reciprocating supporting bar 98 has a bifurcated lower end 106 within which is freely mounted a peripherally grooved roller 107 adapted at times to rest and ride upon the main portion of a guide rail 108, the depending end portions or legs 109 of which are 10 extended through bearing ear 110 provided therefor and projecting from collars 111 carried by a rail supporting bar 112. The legs 109 of the rail 108 are secured in adjustable position by set screws 113 while the collars 111 are in turn secured in adjusted position 15 on the supporting bar 112 by suitable set screws 114 or the like. This supporting bar 112 has one end rigidly secured to a sleeve 115 which is loosely mounted on and 20 may be adjusted longitudinally of the bar 24. A pair of collars 116 are secured upon the bar 24 to either side of the collars 116 to retain the latter in proper position longitudinally of the bar 24. This description 25 will apply to the rail 108 and the supporting means therefor for each reciprocating supporting bar 98, as will be readily understood by referring to Figure 1 of the drawings. Each reciprocating bar 98 is connected 30 with a relief spring 117 connected by one end to an ear or supporting eye 118 projecting from the forward end of the lower portion of the block 102, while the lower end of the spring 117 is connected with a suitable projection 35 119 projecting from the lower bifurcated portion 106 of the reciprocating supporting bar 98. The relief spring 117 will serve to retard slightly the downward movement of the supporting bar 98 for the lower 40 jogging finger 95 and thereby prevent the finger 95 from making an impression on the printed sheet or card with which it is engaged as the printed sheet or card is delivered to the pile and then straightened or 45 pressed downwardly at its lower edge by the finger 95. In order to temporarily retain the reciprocating supporting bar 98 in its uppermost or raised position, I have provided a plurality of teeth 120 along one narrow edge 50 thereof, preferably that extended toward the rear side of the feeding mechanism or feeder and these teeth 120 are adapted to be engaged automatically by the nose or working edge 121 formed on the enlarged and flat- 55 tened head 122 of a latching lever 123. This latching lever 123 is pivoted to one side of the block 102 beneath the jogging table 18 and the working edge or nose 121 is extended into an inwardly directed slot 124 60 formed in the side of the block 102 and con- necting with one side or narrow edge of the slot 101. The latching lever 123 has a long handle 125 extended from the curved or main portion thereof adjacent the head 122 and extended downwardly and forwardly on 65 a line which, if continued, would intersect the line of the main portion of the guide rail 108 and project to one side thereof.

A collar 126 is secured in adjusted position on and longitudinally of the outer section 51 of the bar 49 by a set screw 128 or the like. This collar 126 has a pair of oppositely directed arms 129 which are adapted at times, to engage the handles 125 to swing the same upon the pivots 127 and 70 thereby release the working edges or noses 121 of the levers 123 from the teeth 120 of the bars 98 to permit downward movement of the reciprocating supporting bars 98 and thereby allow the operation of the 75 lower jogging fingers 95 upon the newly delivered printed sheet or card.

While the operation of the jogging mechanism may be clear from the preceding paragraphs taken in connection with the accompanying drawings, the operation may be summed up as follows: The jogging mechanism as well as the parts of the feeder shown in the drawings will illustrate the 80 application of the present invention are 85 shown substantially in the position these parts would occupy upon the completion of the delivery of a printed sheet of paper, a card or the like, and the operation of all 90 of the jogging members or in other words 95 100 the initial position of all of the operative parts. The long levers 12 move outwardly on the cross bar 14 until they engage the cross bar 24. During this initial movement 105 of the long levers 12, the rod 25 swings upon its pivot 26 and at the same time moves upwardly, forcing the rear edges of the jogging table 18 to swing upwardly. This also causes operation of the section rod 49 to swing the upper jogging arm 40 upon its 110 pivot pin or bolt 45, carrying the upper edge of the upper jogging arm 40 forwardly, so as to reduce to the minimum liability of this upper jogging arm 40 interfering with 115 the delivery of a printed sheet or card to the jogging table 18. During the same initial movement of the long levers 12, and the swinging of the jogging table 18, as stated, the springs 74 will be permitted 120 to expand, forcing outwardly the sliding sleeves 71, and thereby moving the end jogging bars 56 outwardly to their inoperative position. This will result in a turning of the cross head 79 and a consequent rotation 125 of the turn rod 81 and a spiral movement 130 thereof upwardly in the socket 86 of the rod 87. The levers 12 will then continue to move outwardly or rearwardly, carrying the cross bar 24 in the same direction and thereby causing operation of the comparatively 130

short levers or feeding mechanism levers 16. As these levers 16 move outwardly, the supporting levers 12 together with the guide rails 108 also move outwardly or rearwardly and upwardly even after the rear end of the jogging table 18 reaches the limit of its upward swinging movement, thereby permitting the guide rails 108 to slide under the rollers 107 and force upwardly the reciprocating supporting bars 98 together with the lower jogging fingers 95 mounted thereon, raising these lower jogging fingers 95 from the jogging table 18 or from upon the stack of printed sheets, cards or the like resting upon said jogging table 18, so as to permit the next printed sheet or card to be delivered to the pile on the jogging table 18 without danger of the lower edge of the sheet or card becoming caught on the lower jogging fingers 95. The supporting bars 98 are retained in raised position by the latching levers 123 catching automatically in the teeth 120 owing to the weight of the lever handles 125 compelling swinging of these levers 123 to operative position. It is to be understood that the printed sheet or card is delivered to the pile on the jogging table 18 at or near the completion of the outer or rear swinging movement of the long levers 12 and it will therefore be seen that at this time all of the jogging members are in their furthest positions from the pile so as not to interfere with the delivery of the printed sheet or card to the pile.

As the long levers 12 and the short levers 16 return to their initial positions so as to gather up new printed and unprinted sheets or cards, as will be readily understood by parties familiar with this art, the levers 12 and 16 move together until the short levers 16 are again in the position shown in Figure 2 of the drawings. During this return movement of the levers 12 and 16, there is only a slight downward movement of the lower end of the jogging table 18 and a partial movement of the upper jogging arm 40 toward the upper edge of the printed sheets or cards on the jogging table 18 and the cross bar 24 returns to position beneath the curved end 94' of depending arm 94. After the levers 16 have completed their return movement, the long levers 12 continue to move inwardly or forwardly, to the position shown in Figure 2 of the drawings. During the latter part of the movement of the long levers 12, the inward or forward swinging movement of the rod 25 continues, thereby completing the movement of the upper jogging arm 40 to its operative position to engage the upper edge of the pile and thereby cause proper alinement of both the upper and lower edges of the sheets of the pile and preventing any of the sheets 65 from projecting past the upper edge of the

pile. During this same operation, the lower edge of the jogging table 18 continues its downward movement, thereby forcing the turn rod 81 downwardly in the socket 86 of the rod 87, as this rod 87 is prevented from moving downwardly by the cross bar 24. This will cause a turning of the cross head 79 to draw the sliding sleeves 71 toward one another on the stationary shaft 72, against the action of the spring 74 and thereby force the movement of the end jogging bars 56 toward the pile of printed sheets or cards until all of the sheets or cards of the pile are properly alined at the opposite ends thereof. Just at the completion of the inward or forward movement of the levers 16, the arms 129 on the collar 126 are forced into engagement with the handles 125 of the levers 123, thereby disengaging the levers 123 from the reciprocating supporting bars 98 and permitting the latter to drop downwardly until the lower jogging fingers 95 engage the upper face of the sheet or card last delivered to the pile, at the lower edge of said sheet or card and thereby prevent turning or curling of this edge of the printed sheet or card.

From the foregoing description of the operation of the parts of the jogging mechanism, it will be seen that these parts cooperate to properly jog or straighten the printed sheets or cards as they are delivered to the pile on the jogging table 18 and the operation of the jogging members is controlled by the movable parts of the feeder to which the present invention is applied. It will also be evident that the upper jogging arm may be readily adjusted by properly positioning the collar 46 upon the stationary supporting rod 47 and regulating the length of the adjustable bar 49. It is also to be understood that the adjustable arms 63 may be lengthened or shortened or folded against the outer faces of the end jogging bars 56 by decreasing the length of the arms 63 until the sections thereof are substantially parallel and then attaching the upper arm 63 to the lower ear 62 and the lower arm 63 to the upper ear 62 of the end jogging bars 56 so as to bring the end jogging bars to position 115 against the arms 66 and 67 of the bars 69. Furthermore, the lower jogging fingers 95 and their supporting and operating means together with the lower stop plates 18^a of the feeder may be moved toward or away 120 from the lower edge of the jogging table 18. By means of the adjustment mentioned, the jogging mechanism may be regulated for operation on sheets or cards of various sizes without altering or substituting parts of either the jogging mechanism or the feeder. It is evident that when adjusting the lower jogging fingers 95, the operating rails 108, must also be adjusted longitudinally of the supporting bars 112.

- It is believed that the complete construction and operation of the present invention may now be clearly understood by a careful reading of the foregoing paragraphs together with the drawings illustrating the invention and it is thought that further description is unnecessary. While the preferred embodiment of the invention is shown and described, however, it is to be understood that minor changes in the details of construction and arrangement of parts may be resorted to within the scope of what is claimed without departing from the spirit of the invention.
- 15 What is claimed is:
1. A jogging mechanism for attachment to the feeder of a printing press comprising the combination with the feeding table and main levers of the feeder, of paper jogging members connected with said table and with the main levers of the feeder to jog the printed paper into an even pile on said table as the sheets are delivered thereto during movement of said table and the main levers 25 of the feeder.
  2. A jogging mechanism for attachment to a printing press feeder comprising the combination with the paper receiving table and main lever of said feeder, of an upper jogging member connected with and adapted to be controlled by movement of the main levers and said table of the feeder, end jogging members adapted to be controlled by movement of said table, and lower jogging fingers adapted to be controlled by movement of the remaining levers of said feeder.
  3. A jogging mechanism for a printing press feeder comprising the combination with the rocking receiving table, the main levers and the main sucker arms of said feeder, of an upper jogging member, end jogging members and lower jogging fingers connected with and adapted to be controlled by movement of said table and the main levers and main sucker arms of the feeder to jog the printed sheets into a pile as they are delivered to said table and prevent damage to the edges of said sheets.
  4. A jogging mechanism for a printing press feeder comprising the combination with the rocking printed paper receiving table of the feeder, of an upper paper jogging member, end paper jogging members, lower paper jogging members, and means 50 for mounting said paper jogging members so as to cause operation thereof during movement of the table in one direction to jog the printed sheets into a pile thereon with the edges even, said means causing movement of 55 said paper jogging members away from the pile of printed sheets during movement of the table in the reverse direction.
  5. A jogging mechanism for attachment to a printing press feeder comprising the combination with the rocking table and other
- movable parts of the feeder, of paper jogging members mounted for movement over the table to jog the pile of printed sheets delivered thereto upon each downward movement of said table, and means for 70 mounting said paper jogging members to cause the operation thereof and return said paper jogging members to inoperative position upon upward movement of said rocking table.
- 75
6. A jogging mechanism for attachment to a printing press feeder comprising the combination with the jogging table and operating levers of said feeder, of an upper jogger arm, adjustable with respect to the upper edge of said table, means connected with certain of said levers for operating said upper jogger arm, end jogger bars, means for mounting said end jogger bars, means for controlling movement of said end jogger bars across said table, and lower jogging fingers for cooperation with the upper jogger arm and the end jogger bars in retaining in a pile the printed sheets delivered to said table.
- 80
- 85
- 90
7. A jogging mechanism for attachment to a printing press feeder having a paper receiving table, main levers and main sucker arms, and a table operating rod connected with said levers, of an upper jogging arm 95 adjustably mounted through the upper edge portion of said table, adjustable connections between said upper jogging arm and the table operating rod whereby operation of the upper jogging arm will be controlled by 100 movement of the table, end jogging bars movable across said table, means for mounting said end jogging bars and controlling movement of the same with movement of the table when the main sucker arms are stationary, and lower jogging fingers for 105 cooperation with the upper jogging arm and the end jogging bars.
- 105
8. A jogging mechanism for attachment to a printing press feeder having a paper receiving table, main levers and main sucker arms, and a table operating rod connected with said levers, of an upper jogging arm 110 adjustably mounted through the upper edge portion of said table, adjustable connections between said upper jogging arm and the table operating rod whereby operation of the upper jogging arm will be controlled by movement of the table, end jogging bars movable across said table, means for mounting said end jogging bars and controlling movement of the same with movement of the table when the main sucker arms are stationary, lower jogging fingers for cooperation with the upper jogging arm and the 115 end jogging bars, operating and controlling means for said lower jogging fingers, and means for controlling the last mentioned means during movement of said table and the main sucker arms.
- 120
- 125
- 130

9. A jogging mechanism for attachment to a printing press feeder including a movable table, main operating levers and main sucker arms, and a table controlling rod connected with said main levers, of an upper jogging arm adapted for swinging movement through the upper portion of said rocking table to jog the upper edges of the printed sheets delivered to said table, connections between said table operating rod and said upper jogging arm, said upper jogging arm being adjustable with respect to the upper edge of said table, end jogging bars adapted for movement across said table, supporting means for said end jogging bars, operating means for said end jogging bars connected with the supporting means therefor, said operating means for the end jogging bars being limited in its movement in one direction by the connecting member of the main sucker arms, and lower jogging fingers to prevent curling of the lower edges of the papers delivered to the pile on said table.
10. A jogging mechanism for attachment to the feeder of a printing press comprising the combination with the feeder rocking table, the lever of the feeder and the operating means for said table, of end jogging bars movable across said table, means carried by said end jogging bars to reduce friction to the minimum, adjustable supporting means for said end jogging bars, operating rods for said end jogging bars connected with the supporting means therefor, controlling mechanism for said operating rods, means to return the controlling mechanism and the operating rods to normal position during movement of said table in one direction, an upper jogging arm, lower jogging fingers for cooperation with said end jogging bars and said upper jogging arm, and means for controlling operation of said lower jogging fingers.
11. A jogging mechanism for attachment to the feeder of a printing press comprising the combination with the feeder rocking table, the lever of the feeder and the operating means for said table, of end jogging bars movable across said table, means carried by said end jogging bars to reduce friction to the minimum, adjustable supporting means for said end jogging bars, operating rods for said end jogging bars connected with the supporting means therefor, controlling mechanism for said operating rods, means to return the controlling mechanism and the operating rods to normal position during movement of said table in one direction, an upper jogging arm, lower jogging fingers for cooperation with said end jogging bars and said upper jogging arm, means for controlling operation of said lower jogging fingers and causing cooperation thereof with the upper jogging arm and said end jogging bars, means for latching the lower jogging fingers in inoperative position on the upward movement of said table, and means for releasing said lower jogging fingers and permitting movement thereof to operative position upon the downward movement of said table.
12. A jogging mechanism for attachment to the feeder of a printing press comprising the combination with the feeder rocking table, the lever of the feeder and the operating means for said table, of end jogging bars movable across said table, means carried by said end jogging bars to reduce friction to the minimum, adjustable supporting means for said end jogging bars, operating rods for said end jogging bars connected with the supporting means therefor, controlling mechanism for said operating rods, means to return the controlling mechanism and the operating rods to normal position during movement of said table in one direction, an upper jogging arm, lower jogging fingers for cooperation with said end jogging bars and said upper jogging arm, means for controlling operation of said lower jogging fingers and causing cooperation thereof with the upper jogging arm and said end jogging bars, means for latching the lower jogging fingers in inoperative position on the upward movement of said table, and means for releasing said lower jogging fingers and permitting movement thereof to operative position upon the downward movement of said table.
13. A jogging mechanism for attachment to the feeder of a printing press comprising the combination with the feeder rocking table, the lever of the feeder and the operating means for said table, of end jogging bars movable across said table, means carried by said end jogging bars to reduce friction to the minimum, adjustable supporting means for said end jogging bars, operating rods for said end jogging bars connected with the supporting means therefor, controlling mechanism for said operating rods, means to return the controlling mechanism and the operating rods to normal position during movement of said table in one direction, an upper jogging arm, lower jogging fingers for cooperation with said end jogging bars and said upper jogging arm, means for controlling operation of said lower jogging fingers and causing cooperation thereof with the upper jogging arm and said end jogging bars, means for latching the lower jogging fingers in inoperative position on the upward movement of said table, and means for releasing said lower jogging fingers and permitting movement thereof to operative position upon the downward movement of said table.
14. A jogging mechanism for attachment to the feeder of a printing press comprising the combination with the rocking table and levers of said feeder, of an upper jogging arm adapted for operation through a slot in the upper portion of said jogging table, said upper jogging arm being adjustable longitudinally of the table, end jogging bars for movement across said table, said end jogging bars having extension members to prevent the lower sheets of paper in the pile on said table from working beneath said end jogging bars, anti-friction rollers carried by said end jogging bars to reduce friction to the minimum, adjustable supporting arms

for said end jogging bars, operating bars for said end jogging bars connected with said adjustable supporting arms, operating mechanism connected with said operating bars whereby said end jogging bars are moved toward one another across said table upon each downward movement thereof, and lower jogging fingers for operation above said table and cooperation with said upper 10 jogging arm and said end jogging bars.

15. A jogging mechanism for attachment to the feeder of a printing press comprising the combination with the rocking table thereof and the adjustable lower stop plates 15 for the paper to be delivered to said table, of an upper jogging arm working through the upper portion of said table for jogging the upper edges of the papers delivered to said table, end jogging bars for movement 20 across said table to jog the ends of the sheets as they are delivered to the pile on said table, lower jogging fingers mounted for operation through said lower stop plates to jog the upper faces of said sheets along 25 the lower edges thereof and prevent curling of the lower edges of said sheets, supporting means and guiding means for said jogging fingers, and operating means for the supporting and guiding means of said lower 30 jogging fingers, said upper jogging arm, the end jogging bars and the lower jogging fingers being adapted for cooperation.

16. A jogging mechanism for attachment to the feeder of a printing press comprising 35 the combination with the rocking table and the lower paper stop plates adjustable thereon, of a supporting bar mounted across the lower edge of said table and having upturned ends, a stationary shaft mounted in 40 the ends of said supporting bar, said supporting bar having a downwardly directed sleeve connected with its central portion and forming a part thereof, collars slidable on said stationary shaft, a rod extended 45 through said sleeve, said sleeve being adapted to be moved longitudinally on said bar, means adjustable on said bar for engagement upon a member of the feeder when the latter moves to position therebeneath, said 50 rod having a socket formed in its upper end, a turn rod extended into said socket and provided with a spiral groove, a lug carried by the inner wall of said socket, a supporting ear extended from said stationary 55 shaft, said turn rod having its upper portion rotatably mounted in said supporting ear, said supporting rod having a squared portion, a cross head mounted on said squared portion, means for connecting the 60 arms of said cross head, with the sliding collars, arms projecting from said sliding collars, end jogging bars mounted on the last mentioned arms and adapted for movement across said table to jog the ends of printed 65 papers delivered thereto, means mounted on

said stationary shaft for causing a reverse movement of said end jogging bars together with the arms supporting the same and the collars, the reverse movement of said collars causing a reverse movement of said cross 70 head and the turn rod, lower jogging fingers for cooperation with the end jogging bars, and an upper jogging arm for cooperation with said lower jogging fingers and said end jogging bars.

17. A jogging mechanism for attachment with the feeder of a printing press comprising the combination with the rocking table thereof carrying the lower paper stop plates, the main operating levers, the connection between the main operating levers and the rocking table, and the lower connecting cross bar of the main sucker arms, of lower jogging fingers for engagement with the upper faces of the sheets adjacent 80 the lower edges thereof after each sheet is delivered to the pile on said table, said jogging fingers being adapted for movement in slots extended in said lower paper stop plates, supporting bars for said lower 85 jogging fingers, guide blocks for said supporting bars mounted in said rocking table and cooperating with the lower paper stop plates to limit downward movement of the lowermost sheets on said rocking table 90 toward the lower edge thereof, supporting rods extended from said lower connecting bar of the main sucker arm and pivotally connected with a stationary part of the press, guide rails mounted on the last mentioned 100 bars, said guide rails being adjustably mounted and serving to force upwardly the supporting bars for said lower jogging fingers, means for latching said supporting bars of the lower jogging fingers in raised 105 position, means for releasing the latching means to permit operation of said lower jogging fingers, end jogging bars for movement across said rocking table for cooperation with said lower jogging fingers, operating 110 mechanism for said end jogging bars adapted to be engaged by the lower connecting cross bar of said main sucker arms, and an upper jogging arm for cooperation with said end jogging bars and said lower 115 jogging fingers.

18. A jogging mechanism for the feeder of a printing press comprising the combination with the rocking table carrying the lower paper stop plates, the main operating 120 lever, the main sucker arms, the connecting lower transverse bar for said main sucker arms, the resilient connecting means between said bar and said main operating levers, and the stationary frame member for the upper 125 edge of said rocking table, of a stationary supporting bar extended from said stationary frame member, an upper jogging arm adjustably mounted on said stationary supporting bar, said upper jogging arm be- 130

- ing adapted for operation through the upper portion of said rocking table, said upper jogging arm having an extension member and means for securing said extension member in adjusted position, an adjustable operating rod for said upper jogging arm pivotally connected with the latter and with the rocking table operating member, lower jogging fingers adapted for operation vertically of said lower paper stop plates, supporting members for said lower jogging fingers, said lower jogging fingers being adapted for adjustment across the supporting members provided therefor, operating mechanism for the supporting members of said lower jogging fingers, said last mentioned operating mechanism being pivotally connected with the cross bar for the lower ends of said main sucker arms and pivotally connected with the stationary frame member for the upper edge of said table, whereby operation of the sucker arms and the table in one direction will cause raising of the supporting bars for said lower jogging fingers, means for latching said lower jogging fingers and supporting bar
- in raised position, means for releasing said lower jogging fingers near completion of the movement of the table and the main operating lever in the reverse direction, means to retard the downward movement of said supporting members for the lower jogging fingers, end jogging bars mounted for movement across said rocking table, supporting means for said end jogging bars, operating means for said end jogging bars adapted to be controlled by movement of the main sucker arms and said table, said lower jogging fingers, end jogging bars and upper jogging arm being adapted for co-operation with one another in jogging sheets delivered to said table and retain the sheets in an even pile with the lower edges of the sheets against the lower paper stop plates.
